UNITED STATES PATENT OFFICE

JOSEPH ALEXANDER MANNING, OF PAWTUCKET, RHODE ISLAND

EYE MOUNTING FOR DOLLS

Application filed January 6, 1932. Serial No. 585,100.

This invention relates to eye mountings for dolls, the primary object of the invention being to provide an eye mounting so constructed that movements of the doll will result in the eyes moving, simulating the movements of the human eye.

An important object of the invention is to provide a mounting of this character constructed in such a way that the eyes may rock laterally resulting in a rolling or glancing motion being imparted to the eyes.

A still further object of the invention is to provide an eye mounting or assembly which is exceptionally cheap to manufacture, and one which may be readily and easily secured in position within the doll face.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a vertical sectional view through a doll head equipped with an eye mounting constructed in accordance with the invention.

Figure 2 is a vertical sectional view through a doll head, taken at right angles to Figure 1.

Figure 3 is a vertical sectional view through a doll head, prior to the positioning of the mounting.

Figure 4 is a sectional view taken on line 4-4 of Figure 1.

Figure 5 is an elevational view of one of the eyes or glass balls forming the eye.

Figure 6 is an elevational view of a mounting.

Figure 7 is a plan view of a mounting.

Figure 8 is a vertical sectional view through a head illustrating a modified form of mounting.

Figure 9 is a vertical sectional view taken at right angles to Figure 8.

Figure 10 is a rear elevational view of a further modified form of mounting.

Figure 11 is a detail view of the weight used with one form of the invention.

Referring to the drawings in detail, the reference character 5 designates a doll head, which is constructed of the usual and well known material, the same being provided with eye sockets, curved to conform to the curvature of the eyes or glass balls, commonly used in doll construction.

The eye mounting in the preferred form of the invention, includes a stamping in the form of a plate 6, the same being provided with extensions 7 formed intermediate its ends.

These extensions 7 have openings to receive the ends of the U-shaped securing member 8, that is embedded within the material of which the head is formed, so that the ends of the U-shaped member extend beyond the inner surface of the head, where they pass into the openings formed in the stamping or plate 6.

The extended ends of the U-shaped securing member are now bent over the plate 6, as clearly shown by Figure 4 of the drawings, securely fastening the plate in position.

Forming a part of the plate, are sockets 9 of sizes to accommodate the eye balls 10 in such a way that the eye balls may swing freely within the mounting, but at the same time will not rattle.

Each of the sockets 9 is formed with a cut out portion having a substantially straight lower edge 11, and a curved upper edge 12, the lower edges of the sockets 9 being disposed directly opposite to eye openings formed in the head, for purposes to be herein-after more fully described.

Extending rearwardly from each eye ball, is a rod 13, which is provided with an opening to receive the rivet 14 associated therewith. Connected with the rods 13 of the adjacent eye ball, is an arm 15 which is also in the form of a stamping, the arm being of a length to extend the entire distance between the rods 13. As clearly shown by Figure 1 of the drawings, the arm 15 extends downwardly an appreciable distance, where it is provided with a weight 16, the weight acting to exert

a downward pull on the rods 13, to hold the eye balls in their proper positions, when the doll is held in an upright or vertical position.

When the doll is laid down in a horizontal position, the weight 16 will of course move the eye balls to positions to lend a sleeping appearance to the doll. Should the doll be moved laterally, the eye balls will swing laterally, resulting in a roll or glancing motion 10 being imparted to the eyes.

In the form of the invention as shown by Figures 8 and 9 of the drawings the mounting comprises a body portion formed of a length of wire 17, which has offset portions 18 15 curved to conform to the curvature of the eye balls 19, portions of the offset portions extending forwardly where they are provided with eyes 19 providing means whereby securing members may be provided to secure the 20 mounting in position.

Disposed intermediate the ends of the body portion 17, are offsets 20 providing an eye to accommodate the ends of the U shaped securing member 21, which has its ends bent 25 over the offsets, as shown by Figure 8.

An arm 15 is provided with this form of mounting, which arm is supplied with the weight 16 as previously described.

By this construction, it will be seen that 30 a flat supporting surface is provided, and stops are formed in the ends thereof to restrict lateral movement of the eye balls.

A modified form of weight is shown by Figures 10 and 11 of the drawings, and comprises an arm 22 bent to provide an offset 23, and laterally extended ends 24, the ends 24 being secured to the rods that extend from the eye balls.

Mounted within the offset portion 23 is a 40 weight 25 that acts to move the eye balls, as the doll supplied with the mounting, is tilted to various angles.

In view of the foregoing detailed description, it is thought that a further detailed description as to the operation of the device is unnecessary.

I claim:

1. The combination with a doll head having eye sockets, of an eye mounting comprising a plate fitted over the eye sockets and having socket portions registering with the eye sockets, eye balls fitted within the sockets and held in place by the plate, said socket portions of the plate having cut out portions defining 50 elongated flat lower edges and curved upper edges, rods extending from the eye balls and passing through the cut out portions of the plate, said rods resting on the flat lower edges of the cut out portions, and weights connected to the free ends of the rods for moving the eye balls within their sockets.

2. The combination with a doll head having eye sockets, of an eye mounting comprising a plate having sockets, means for securing the plate to the head, the sockets of the

plate and head being in registry, eye balls fitted in the sockets, the socket portions of the plate having substantially large openings, rods extending from the eye balls and passing through the openings and movable transversely and vertically within the openings, an arm secured to the rods and depending therefrom, and a weight on the arm for moving the arm by gravity to operate the eye balls, when the doll head is moved.

In testimony that I claim the foregoing as my own, I have hereto affixed my signature.

JOSEPH ALEXANDER MANNING.
